CLAIM

The ornamental design for a cap for toothpaste tube, as shown and described.

DESCRIPTION

FIG. 1 is a perspective view of a cap for toothpaste tube, showing my new design;

FIG. 2 is a front view thereof;

FIG. 3 is a rear view thereof;

FIG. 4 is a right-side view thereof;

FIG. 5 is a left-side view thereof;

(Continued)

FIG. 6 is a top view thereof; and,
FIG. 7 is a bottom view thereof.

1 Claim, 7 Drawing Sheets
